UNITED STATES PATENT OFFICE

HUGO SCHMEISSER, OF SUHL, GERMANY

REPEATING AIR GUN

Application filed December 11, 1928, Serial No. 325,179, and in Germany December 13, 1927.

My invention relates to repeating air guns or pistols and more particularly to an air gun of the said character having a movable magazine for projectiles which is automatically fed upon operation of the cocking mechanism.

The main object of my invention is to provide a particularly advantageous construction and arrangement of the magazine, so that both spherical bullets, and, if desired or preferred, cylindrical projectiles or so-called diabolo-projectiles may be fired, and the invention consists essentially in constructing and arranging the magazine on the barrel over and above the axis of the bore thereof in a manner that the several chambers or pockets of the magazine receiving the single projectiles, will be adjustable over or with relation to the aperture of a charging valve provided in the barrel for the purpose of transferring the projectiles singly from the magazine to the bore of the barrel.

With the above recited and other objects in view reference is had to the following specification and the annexed drawings in which there is exhibited one example or embodiment of the invention which is in no way intended as a limitation upon the scope of the subjoined claims as it is to be clearly understood that variations and modifications which fairly fall within the true scope of said claims may be resorted to when found expedient.

In the accompanying drawings forming a part of this specification and showing, as above stated, for purposes of exemplification only, a preferred form and manner in which the invention may be embodied and practised, but without limiting the claimed invention to such illustrative instance:

Figure 1 represents a side elevation of that portion of an air rifle constructed according to the present invention, to which the invention relates, with the air-plunger in its frontal end position or position of rest; Figure 2 is a view in longitudinal section thereof with the air-plunger in an intermediate position and the correspondingly displaced cocking lever, the cocking bar and other co-operating members shown in dotted

lines. Figure 3 is a view in top plan of the same with the magazine filled with bullets and the cover plate thereof so turned that the filling or show apertures thereof are displaced with relation to the pockets of the magazine and the bullets thus are prevented from escaping therefrom accidentally: Figure 4 is a view similar to Figure 3, but with the cover plate removed from the magazine, so that the inner construction thereof, especially that of the charging pockets and the feeding mechanism are exposed; Figure 5 is a view in top plan of the charging valve; and Figure 6 is a side elevation thereof.

Corresponding and like parts are referred to in the following description and indicated in all the views of the drawings by the same reference characters.

The barrel 1 is rigidly connected or integral with the cylinder 2 forming the air chamber and enclosing the air-plunger 3 in the usual manner so that the latter is adapted to be displaced towards the rear end of the cylinder or air chamber and forced towards the front end thereof by the main spring 4.

Mounted in the plane of the bore of the barrel and transversely thereto at a point near the rear end of the barrel is a charging valve 5 having a conical bore 33 in a vertical plane coinciding with the vertical plane of the bore of the barrel, the front or bottom end of the bore 33 which is somewhat narrower than the rear or top end thereof, being of a somewhat greater diameter than the bore of the barrel. The charging valve 5 is adapted to be turned and firmly connected, at its left-hand outer end, with a two-armed lever whereof the longer front arm 6 is pivoted to a link 7, while the shorter rear arm 8 thereof, is provided with a bore for the accommodation of a feeding pin 9 equipped with a coiled spring 10 encircling the same, and a screw 11 in its one end as will be seen in Figure 5.

The link 7 is pivotally connected with the cocking lever 13 by means of a screw-pivot 12 so that when the lever 13 is moved and displaced for about 90° the charging valve 5 will also be positively displaced for 90° or from its horizontal position, as shown in Figure 1, to a vertical position, not fully shown

in Figure 2, or vice versa. The cocking lever 13 is adapted to rotate about the pivot 14 and pivotally attached to the cocking bar or sear 16 by means of a pivot 15. When the cocking lever 13 is manually moved downwards or off the barrel 1, as shown in Figure 2, the sear 16 connected with the plunger 3 in the usual manner, will act to force the plunger into the cocked position.

10 Mounted on the rear end of the barrel in a plane parallel to the horizontal plane of the bore is a magazine comprising a stationary bottom plate 21, a revoluble cylindrical container or magazine 17, properly speaking, and 15 a cap or cover 24. The magazine 17 is adapted to revolve about a vertical stud 18 rigidly connected with the barrel, and provided with a number of peripheral chambers or pockets 19 for the reception of a corresponding number 20 of projectiles. The periphery of the magazine 17 is serrated and the number of the marginal teeth 20 thus produced corresponds to the number of pockets 19. The revoluble magazine 17 is supported by the stationary 25 plate or disk 21 which is prevented from rotation by a pin 22 fixed in the barrel and engaging in a hole of the plate 21. Further the plate 21 is provided with an aperture in axial alinement with a vertical bore 23 of the 30 barrel which in turn is in axial alinement with the conical bore 33 of the valve when the latter is fully opened for allowing a projectile to drop into the valve bore, as will be readily understood on inspection of Figure 2.

10 The cover plate or cap 24 is pivotally attached to the stud 18 by means of a screw 25 so as to cover and laterally enclose the magazine 17 in concentric superposition with relation to the latter. The plate or 15 cap 24, however, is adapted to revolve for a small range of about one half of the diameter of a projectile only, suitable stops, abutments or notches and an arresting pin 26 being provided for arresting the cap 24 in the 20 two end positions of the said revolving range. To this end the pin 26 is movably housed in a slanting bore of the rear end of the barrel and supported therein by a coiled spring 27 tending to force the pin 26 out of the slanting bore and hereby causing the outer end 25 or point thereof to engage in the one or the other one of two notches 28 provided in the peripheral surface of the cover or cap 24. In the top of the latter there are provided 30 show and filling openings 29 arranged in a circle so as to conform to the underlying pockets 19 and occupying a position in vertical alinement with the latter, when the rotatable cap 24 is in its filling position, that is 35 to say, when the cap has been turned by hand in counterclockwise direction as far as to be arrested by the stop or abutment, the show openings 29 will accurately register with the pockets 19 of the magazine so as to allow of 40 filling the magazine by dropping the pro-

jectiles through the openings 29 into the pockets 19, whereupon the cap 24 is turned in clockwise direction as far as to be arrested by the second stop or abutment. The extent or range of the angular movement of the 70 cap is determined by the distance between the two stops or abutments and amounts, in the common circular centre line of the openings 29, to about one half of the diameter of the openings 29, or the pockets 19 only so 75 that when the cap has been turned in clockwise direction to the end of its moving range, the pockets 19 and the projectiles therein will be or lie partially covered by the cap, as shown in Figure 3, and the projectiles be 80 prevented from dropping out of the pockets 19 upon turning the rifle upside down.

The outer surface of the annular part of the cap is knurled to afford a better grip. The springy rings 30 and 31 surrounding the 85 stud 18 are adapted to contact with and exert a slight pressure against the cap 24, but the main purpose of the rings resides in the braking action they exercise upon the magazine in order that the latter be prevented 90 from accidental or automatic feeding movements.

In the embodiment shown the magazine is of cylindrical or drum shape. Obviously the same may be given any other appropriate 95 configuration and may be disposed in inclined position, that is at an angle to the axis of the bore of the barrel, instead of parallel thereto as shown. Furthermore, there may be provided mechanical means for operating 100 the magazine by means of spring action or the like in connection with a releasable ratchet pawl, in lieu of operating the same manually as in the embodiment illustrated and de- 105 scribed.

When the magazine 17 has been supplied with projectiles and the cap 24 has been turned in clockwise direction in the manner hereinbefore described, so that the pockets 19 and the projectiles therein are partially covered, the charging of the rifle for the firing purpose is effected in the following manner.

The cocking lever 13 is swung by hand to the rear whereby the charging valve 5 will be turned for 90° through the agency of the link 7 and the valve lever 6, 8 pivotally connected therewith. Consequently the bore 33 of the valve then will occupy a vertical position exactly below and in vertical alinement with the first pocket 19 of the magazine so that the projectile will drop, due to gravity, into the bore 33. Simultaneously with the rotation of the charging valve 5 the feeding pin 9 of the short arm 8 of the valve lever is operated to feed the magazine by the width of one tooth corresponding to the angular length of one pocket 19, in order that the first pocket be brought into vertical alinement with the bore 33.

Next to this the cocking lever 13 is swung by hand back to its horizontal or closed position shown in Figure 1 with the result that the valve 5 will be turned back at the same time, so that the bore 33 thereof with the 5 projectile therein will reoccupy a horizontal position in axial alinement with the bore of the barrel and the front or muzzle portion of the bore will or would be in communication with the rear portion thereof and the air chambers, but for the projectile in the bore. The rifle thus is charged and cocked or ready 10 for firing.

The described manipulation of the cocking lever is repeated, upon firing a shot, for 15 a next discharge and so on until the magazine is emptied.

What I claim is:—

1. A repeating air-gun, comprising a barrel, a magazine for projectiles, mounted on 20 the said barrel, so as to be adapted for intermittent rotation, a charging valve supported in a transverse bore of the barrel, a charging lever, a two-armed lever rigidly connected with the said charging valve, means for pivotally connecting one arm of the said two-armed lever with the said charging lever, and a feeding pawl or pin attached to the other arm of the said two-armed lever and adapted 25 to co-operate with the said magazine for feeding the latter upon operation of the manually operable cocking lever.

2. A repeating air-gun, comprising a barrel, a magazine mounted on the barrel and 30 having pockets therein for the projectiles, a rotatable cap concentrically mounted on the magazine and projecting over the sides thereof to cover and laterally close the magazine, said cap having openings therein corresponding with the pockets in the magazine, and means for limiting the rotatable movement of 35 the cap to an extent that in one end position the pockets and openings coincide for loading purposes and in the other end position being out of alignment.

3. A repeating air-gun, comprising a barrel, a magazine mounted on the barrel and having pockets therein for the projectiles, a rotatable cap concentrically mounted on the 40 magazine and projecting over the sides thereof to cover and laterally close the magazine, said cap having openings therein corresponding with the pockets in the magazine and a pair of spaced notches in the lateral side, and a spring-pressed pin mounted on the barrel 45 and cooperating with the notches in the cap for limiting the rotatable movement thereof to an extent that by one notch the pockets and openings coincide for loading purposes and by the other notch the pockets and openings 50 are out of alignment in closed position.

In testimony whereof, I affix my signature.
HUGO SCHMEISSER.
